UNITED STATES PATENT OFFICE.

EDWARD J. THURBER, OF NEW ORLEANS, LOUISIANA, ASSIGNOR TO THURBER ROTARY STARTER CO., INCORPORATED, OF NEW ORLEANS, LOUISIANA.

ROTARY SELF-STARTER.

1,058,811.

Specification of Letters Patent.

Patented Apr. 15, 1913.

Application filed August 28, 1912. Serial No. 716,634.

To all whom it may concern:

Be it known that I, EDWARD J. THURBER, residing at New Orleans, in the parish of Orleans and State of Louisiana, have invented certain new and useful Improvements in Rotary Self-Starters, of which the following is a specification.

My invention relates to the art of internal combustion engine starters, and the invention primarily has for its object to provide a simple, compactly arranged, self-contained and inexpensive starting apparatus of a neat appearance that will not take up any unnecessary room or add much weight to the power plant.

The invention is primarily designed for use on automobile and marine engines of the gas engine type and the invention generally embodies in one compact structure, a fluid operated starting rotary engine and a train of reduction gears of the planetary type together with an automatic clutch device for operatively connecting the starter with the driven shaft of the internal combustion engine, the clutch being of the self-releasing type whereby as the engine speeds up beyond that of the driving element of the clutch, the starter will become automatically disengaged from the gas engine shaft.

My invention also makes provision for the use of a starting crank directly connectible to the engine shaft, when desired, as for example, when, for some reason or the other, the starter becomes inoperative.

More subordinately, the invention includes those novel details of construction, combination and arrangement of parts, all of which will be first fully described, then be specifically pointed out in the appended claims, and illustrated in the accompanying drawings, in which:

Figure 1, is a central vertical longitudinal section of the invention. Fig. 2, is a cross section on the line 2—2 of Fig. 1. Fig. 3, is a section on the line 3—3 of Fig. 1. Fig. 4, is a section on the line 4—4 of Fig. 1. Fig. 5, is a detail perspective view of the gripping end of the crank.

In the drawings, in which like letters and numerals of reference indicate like parts in all of the figures,—1 designates the main frame or web on one side of which is an annular rim 3 that is disposed eccentrically with relation to the shaft bearing 2 to form,

in connection with the web 1 and cap plate 55, the piston chamber of the rotary engine.

To the rim 3, the outer face plate or cover 5, is fastened as at 7. The cover 5 has a bearing 6 and the starter shaft 10 is mounted in the bearings 2 and 6. The opposing faces of the cover 5 and web each have an internal annular flange 8, the flanges 8 being disposed eccentrically to the shaft 10. 44 is the rotor, which consists of the inner web that fits between the flanges 8 and is keyed as at 11 to the shaft 10; it also includes the annular flanges 45 which are arranged concentrically to the shaft 10. The rotor is slotted at 9 to receive the pistons 12 which are of the T form and include shoulders 13 to ride on the flanges 8 and reciprocate in the slots 9.

14 represents the fluid inlet which communicates with the fluid feed pipe 15, the spent fluid exhausting through the outlet 75 16 and exhaust pipe 17. The starter is supported by its base 18, which may be fastened to some fixed part of the bed of the machine on which it is to be used. The main frame 1 also includes a rim 4 on the 80 side opposite the rim 3, the rim 4 being of greater diameter than the rim 3 and the rim 4 is disposed concentrically to the shaft 10. The shaft 10 extends beyond the central web of the rim and carries a pinion 85 19 which is connected to it at 20.

21 are the planetary gears that turn on stub shafts 22 carried by the web 1 and the gears 21 continuously mesh with the pinion 19 and with the internal rim gear 23 90 that is fastened at 25 to the disk 24. The disk 24 has an offset portion 26 to form a recess 27 that receives the clutch side plate 28 which is bored to turn on the non-toothed extension 46 of the pinion 19. 29 is the 95 other clutch side plate that is secured to turn with the plate 28, and with the driven shaft clutch element 32 by screw bolts 38. The side plates 28—29 each have a ball recess 30 for the reception of the bearing 100 balls 31. The offset portion 26 of the disk 24 is bored to receive the clutch element 32, and itself serves as one of the clutch elements. The clutch element 32 has pockets 39 to contain the clutch rollers 40. In order 105 to lubricate the gears 21—23, etc., the frame 1 has a lubricant bore 41 to which suitable lubricant may be fed from a cup 42.

The driven shaft 35, when my invention is in use on automobile engines, may be the engine shaft itself, and it is bored at 36 to receive the starting crank 43 that projects through the hollow shaft 10, the shaft 35 being provided with a cross pin 37 to fit the slotted end 47 of the crank 43.

The manner in which my invention operates is as follows:—When compressed air 10 or other motive fluid is admitted into the pipe 15, it enters the rotor chamber and starts the rotor 44 in motion. The motion of the rotor 44 is transmitted, through the shaft 10 and pinion 19, to the planetary 15 gears 21 and by them the motion is transmitted to the rim gear 23 which turns the disk 24—26 in the direction of the arrow in Fig. 2. The shaft 35 being at this time at rest, the rollers 40 will creep along the inclines of the pockets 39 to act as wedges 20 and cause the clutch elements 32—26 to be united, as it were, whereby the motion of the disk will be transmitted to the shaft 35 and start the engine into operation. As 25 soon as the speed of rotation of the shaft 35 exceeds that of the disk 24—26, the rollers 40 will creep back into the deeper portions of the pockets or recesses 39, and the clutch elements 26—32 will become automatically 30 disconnected. The transmission gearing of the starter is covered by a cap plate 48 which is secured at 50 to the rim 4, the plate 48 being recessed to receive the disk 29 and the offset portion 26 and it is also provided with 35 a shaft bearing 49 that is counter-bored to receive the non-toothed portion of the clutch element 32.

From the foregoing description, taken in connection with the accompanying drawings, it is thought the complete construction, 40 operation and advantages of my invention will be readily understood by those skilled in the art to which it appertains.

What I claim is:

45 1. In a starter, a main frame including a central web having a shaft bearing and side annular rims, one of which rims is eccentric and the other is concentric to said bearing, a cover plate secured to said eccentric rim 50 to form a rotor chamber, a rotor and its pistons mounted within said chamber, means for admitting working fluid into said chamber and exhausting it therefrom, said cover plate having a bearing, a driving shaft 55 mounted in said bearings and carrying said rotor, a second cover plate secured to said concentric rim to inclose a transmission chamber, said second cover plate having a shaft bearing, a driven shaft mounted in 60 said last named bearing and power transmitting gearing within said transmission chamber for operatively connecting said shafts together.

65 2. In a starter, a main frame including a central web having a shaft bearing and side

annular rims, one of which rims is eccentric and the other is concentric to said bearing, a cover plate secured to said eccentric rim to form a rotor chamber, a rotor and its pistons mounted within said chamber, means 70 for admitting working fluid into said chamber and exhausting it therefrom, said cover plate having a bearing, a driving shaft mounted in said bearings and carrying said 75 rotor, a second cover plate secured to said concentric rim to inclose a transmission chamber, said second cover plate having a shaft bearing, a driven shaft mounted in said last named bearing and power transmitting mechanisms for operatively connecting 80 said shafts together, said transmitting mechanism including a train of gearing.

3. In a starter, a main frame including a central web having a shaft bearing and side annular rims, one of which rims is eccentric 85 and the other is concentric to said bearing, a cover plate secured to said eccentric rim to form a rotor chamber, a rotor and its pistons mounted within said chamber, means for admitting working fluid into said chamber and exhausting it therefrom, said cover plate having a bearing, a driving shaft mounted in said bearings and carrying said 90 rotor, a second cover plate secured to said concentric rim to inclose a transmission chamber, said second cover plate having a shaft bearing, a driven shaft mounted in said last named bearing and power transmitting mechanisms within said transmission 95 chamber for operatively connecting said shafts together, said transmitting mechanisms including a train of gearing and a self-operating clutch.

4. In a starter, a support including an eccentric and a concentric rim with an internal partition web having a shaft bearing and located between said rims, covers secured to said rims to form respectively a rotor chamber on one side of said partition and a transmission chamber on the other 110 side of the same, said covers having shaft bearings, a driving shaft and a driven shaft mounted in the aforesaid bearings, a rotor within said rotor chamber on said driving shaft, transmission gearing and a clutch device within said transmission chamber for transferring the power of said driving shaft to said driven shaft.

5. In a starter, a support including an eccentric and a concentric rim with an internal partition web having a shaft bearing and located between said rims, covers secured to said rims to form respectively a rotor chamber on one side of said partition and a transmission chamber on the other 115 side of the same, said covers having shaft bearings, a driving shaft and a driven shaft mounted in the aforesaid bearings, a rotor within said rotor chamber on said driving shaft, a transmission mechanism and clutch 120

125

130

device within said transmission chamber for transferring the power of said driving shaft to said driven shaft, said transmission mechanism and clutch device including a driving 5 pinion on the driving shaft, intermediate gears carried by said partition to mesh with said pinion, an internal rim gear meshing with said intermediate gears, a disk for carrying said rim gear, and a clutch connection 10 between said disk and said driven shaft.

6. In a starter, a support including an eccentric and a concentric rim with an internal partition web having a shaft bearing and located between said rims, covers secured to said rims to form respectively a rotor chamber on one side of said partition and a transmission chamber on the other side of the same, said covers having shaft bearings, a driving shaft and a driven shaft 20 mounted in the aforesaid bearings, a rotor within said rotor chamber on said driving shaft, a transmission mechanism and clutch device within said transmission chamber for transferring the power of said driving shaft 25 to said driven shaft, said transmission mechanism and clutch device including a driving pinion on the driving shaft, intermediate gears carried by said partition to mesh with said pinion, an internal rim gear meshing 30 with said intermediate gears, a disk for carrying said rim gear, said disk having an offset clutch element forming portion, a clutch element on said driven shaft, side disks secured to said last named clutch element to embrace said offset portion, and connecting elements between said clutch elements.

7. In a starter, a support including an eccentric and a concentric rim with an internal partition web having a shaft bearing and located between said rims, covers secured to said rims to form respectively a rotor chamber on one side of said partition and a transmission chamber on the other 45 side of the same, said covers having shaft bearings, a driving shaft and a driven shaft mounted in the aforesaid bearings, a rotor within said rotor chamber on said driving shaft, a transmission mechanism and clutch 50 device within said transmission chamber for transferring the power of said driving shaft to said driven shaft, said transmission mechanism including a driving pinion on the

driving shaft, intermediate gears carried by said partition to mesh with said pinion, an 55 internal rim gear meshing with said intermediate gear, a disk for carrying said rim gear, said disk having an offset clutch element forming portion, a clutch element on said driven shaft, side disks secured to said 60 last named clutch element to embrace said offset portion, said side disks and said offset portion having coöperating ball races and balls held therein, and self-releasing connecting elements between said clutch elements. 65

8. In a starter, a support including an eccentric and a concentric rim with an internal partition web having a shaft bearing and located between said rims, covers secured to 70 said rims to form respectively a rotor chamber on one side of said partition and a transmission chamber on the other side of the same, said covers having shaft bearings, a driving shaft and a driven shaft mounted 75 in the aforesaid bearings, a rotor within said rotor chamber on said driving shaft, a transmission mechanism and clutch device within said transmission chamber for transferring the power of said driving shaft to 80 said driven shaft, said transmission mechanism and clutch device including a driving pinion on the driving shaft, intermediate gears carried by said partition to mesh with 85 said pinion, an internal rim gear meshing with said intermediate gear, a disk for carrying said rim gear, said disk having an offset clutch element forming portion, a clutch element on said driven shaft, side disks secured to said last named clutch element to 90 embrace said offset portion, said side disks and said offset portion having coöperating ball races and balls held therein, self-releasing connecting elements between said clutch elements, said pinion having a smooth 95 projection, one of said side disks being bored to receive said smooth projections, one of said cap plates having a counterbore portion and said driven shaft clutch element having a smooth bearing member to 100 project into said counterbore portion, and means for feeding lubricant to said gearing.
